UNITED STATES PATENT OFFICE.

JOHN McCausland, of Providence, Rhode Island.

PAPER PIPING.

SPECIFICATION forming part of Letters Patent No. 291,872, dated January 1, 1884.

Application filed September 18, 1883. (No model.)

To all whom it may concern:

Be it known that I, JOHN McCausland, a citizen of the United States, residing at Providence, in the county of Providence, in the State 5 of Rhode Island, have invented a new and useful Paper Piping, of which the following is a specification.

My invention relates to a pipe made of paper, paper-pulp, and paper-pulp and textile 10 fabric interlaid, and the lengths thereof jointed by couplings of the same material.

The object of my invention is to provide a cheap, practicable, and serviceable substitute for metallic pipes.

15 I design to use my invention more particularly for speaking-tubes, and air and water conductors.

In the drawings, Figure 1 represents a speaking tube constructed of paper. Fig. 2 is a 20 longitudinal section, showing the mode of coupling two lengths of pipe together. Fig. 3 is a sectional end view, showing the manner of interlaying the paper and textile fabric.

A represents the straight lengths of pipe, 25 which are made of paper, or paper-pulp, or paper-pulp and textile fabric interlaid. The lengths are connected together by couplings c', made of the same material or materials as the pipe, and shrunk onto the ends of the pipe- 30 lengths. The elbow-joints E are made of metal, rubber, or other suitable material.

S represents the mouth-piece of a speaking- tube.

a represents the pulp or paper, and b the textile 35 fabric.

I have found that interlaying the paper or pulp with some textile fabric strengthens the pipe materially, that it cannot be broken, and that it is more impervious to water or dampness. I form the pipe of paper or pulp on a 40 cylindrical former, and if it is to be used as a water-conductor I shellac or japan it on the outside and inside.

The great disadvantage, aside from the cost, in the use of metallic speaking-tubes arises 45 from the reverberation, which renders the tone indistinct and confused in speaking through tubes of any considerable length, or having many turns in them.

In practical operation it has been proved 50 that pipes constructed after my invention, of paper or interlaid textile fabric and paper, do not deaden the sound, and that there is no reverberation, the tone coming clear and distinct at all times.

55 I claim as my invention and desire to secure by Letters Patent—

1. A pipe for speaking-tubes and other purposes, constructed of paper tubes A, connected together by elbows E, of metal, rubber, or other suitable material, and paper couplings c', as shown and described.

2. A pipe for speaking-tubes, and air and water conductors, constructed of alternated layers of paper a and textile fabric b, as shown 65 and described.

JOHN McCausland.
